UNITED STATES PATENT OFFICE.

SHELTON T. CAMERON, OF WASHINGTON, DISTRICT OF COLUMBIA, AND EDWARD R. INMAN, OF FRANKLIN, PENNSYLVANIA.

PACKER FOR OIL-WELLS.

1,318,352.

Specification of Letters Patent.

Patented Oct. 14, 1919.

Application filed June 17, 1918. Serial No. 240,432.

To all whom it may concern:

Be it known that we, SHELTON T. CAMERON, of Washington, District of Columbia, and EDWARD R. INMAN, of Franklin, Pennsylvania, have invented a new and useful Improvement in Packers for Oil-WellS, which invention is fully set forth in the following specification.

This invention relates to packers for oil wells, and has for its object to provide a packer of this description which shall be simple in its construction, inexpensive to manufacture, and highly efficient in operation. Heretofore the most efficient oil well packers have employed rubber to a greater or less extent in their construction, particularly for the packing element. This is especially the case where the weight of the superimposed column of water is relied upon to force the packer into efficient packing contact with the well tubing and the walls of the well after the same has been placed in position. One of the troubles with rubber is found in the fact that after it has been for a considerable time in position in the well it becomes hard or "set," rendering it difficult to remove the same from the well for repairs or replacement. Moreover, rubber is quite expensive, and it is essential, particularly when wells of small flow are pumped, to reduce the operating expenses to a minimum if the well is to be operated at a profit at all. The packer has heretofore been found one of the expensive elements in connection with oil well operation, and a further object of the invention is to provide a packer which is composed of cheap materials, without reducing its efficiency in operation, and at the same time facilitating its ready removal from the well for inspection, repair or replacement.

With these objects in view, the invention consists in the construction and combination of elements hereinafter described and then specifically defined in the appended claims.

The inventive idea is capable of being embodied in a variety of structures, some of which, for the purpose of illustrating the invention are shown in the accompanying drawings, but it is to be expressly understood that such drawings are for the purpose of illustration only, and are not designed to

define the limits of the invention, reference being had to the claims for this purpose. 55

In said drawings, Figure 1 is a vertical, longitudinal section of one form of the invention, the well tubing and the gas escape pipe being shown in side elevation, with the walls of the well indicated by vertical dotted lines, and the parts being shown in the position which they occupy while being placed in the well;

Fig. 2 is a side elevation of the packer and its connected well tubing and gas escape pipe, the walls of the well being indicated by the full vertical lines, and the parts being shown in packing position;

Fig. 3 is a transverse section on the line III—III of Fig. 1; 70

Fig. 4 is a transverse section of Fig. 1 on the line IV—IV;

Fig. 5 is a transverse section of Fig. 1 on the line V—V;

Fig. 6 is a view partly in vertical section 75 and partly in side elevation of another form of the invention;

Fig. 7 is a top plan view of Fig. 6;

Fig. 8 is a vertical, longitudinal section of still another form of the invention, in which 80 no gas escape pipe is employed; and

Fig. 9 is a section on the line IX—IX, Fig. 8.

Referring to the drawings, in which like reference numerals refer to corresponding parts throughout the several views, and referring first to Figs. 1 to 5 inclusive, 1 is the well tubing through which fluid is pumped from the well. 2 is a bolster or abutment secured to the well tubing in any suitable way, as by screw-threads. Mounted on the well tubing 1 and resting on the bolster 2 is a packing sleeve 3 composed of a suitable fibrous material, preferably asbestos fiber, and a suitable binder. It is essential that the sleeve 3 should be sufficiently firm to readily hold its shape under the rough handling to which it is subjected while the packer is being placed in the well, but which shall become sufficiently plastic, when in 100 position in the well, to expand under the pressure of the column of water above the packer in the well to be forced into intimate packing contact with the walls of the well, the surface of the well tubing, and of the 105 gas escape pipe, when the latter is em-

ployed. We have discovered that a suitable binder for this purpose may be made by dissolving resin in benzol, and adding to this solution a mixture consisting of benzol and 5 a suitable soap stock lubricant. The fiber is then thoroughly saturated with this mixture, and molded to a proper degree of density under pressure, any excess of the binder being expressed thereby. Preferably, as indicated above, asbestos fiber is employed, and for the binder we dissolve three ounces by weight of resin in ten ounces by measure of benzol, and when this has become thoroughly dissolved, we add a mechanical 10 mixture consisting of three ounces of benzol and two ounces of the soap stock lubricant, which is preferably composed of talow, mineral oil, soda lye and water.

The sleeve produced as above becomes very 20 hard upon drying, but will quickly soften when in the presence of water in the well, and hence produces an ideal packing.

Still referring to Figs. 1 to 5, 4 is a head of any suitable substance, as metal, mounted 25 to have longitudinal movement on the tubing above the sleeve 3, and 5 is any packing material, as for example, that which is employed in making the sleeve 3, mounted in an annular recess in the head 4 and 30 rounding the well tubing 1 and the gas escape pipe 6. Mounted to fit within the recess in the head 4 above the packing 5 is a gland 7 into which the gas escape pipe 6 is preferably screw-threaded, as shown in Fig. 35 1. This gland is flanged as shown at 8, and resting upon said gland and supported by the flange thereof is a seal or packing cup 9 of any suitable flexible material, as leather, upon which rests a head 10 longitudinally 40 movable upon the tubing 1 and composed of any suitable material, preferably metal. The seal or packing cup 9 is preferably secured to the flanged portion 8 of the gland 7 by screws 11 (Fig. 3). In addition to the 45 opening through which the well tubing 1 passes, the cap 10 is provided with a suitable socket and opening for receiving the lower end of the upwardly projecting portion of the gas escape pipe 12, as clearly shown in 50 Fig. 1. The entire packing is held in place on the tubing 1 by a standard tube coupling 13. Another similar tube coupling 14 is screw-threaded onto the lower end of the tubing 1, and the upper and lower sections 55 of the well tubing are connected to these couplings 13 and 14 in the usual way.

Operation: The cap 10, packing cup 9, gland 7, packing 5 and head 4 are all free to move downward, and the diameter of the 60 bolster 2, the packing sleeve 3 and the head 4 is slightly less than that of the well to be packed, while the diameter of the packing cup 9 is approximately that of the well, so that it fits smoothly and snugly within the 65 well, without being too tight or causing too

much friction, all as will be readily understood from an inspection of Fig. 1.

When the packer is placed in the well and the pumping operation started, thus exhausting the water beneath the packer, the weight 70 of the water above the packer, which is sustained by the cup 9, causes the cup structure to move downward, the first effect of which is to compress the packing ring 5 firmly 75 around the tubing 1 and the gas relief pipe 6. Thereupon, the head 4 also moves downward, causing the plastic sleeve 3 to expand and completely fill the bore of the well or the well casing, the parts then occupying the 80 position shown in Fig. 2.

It will be observed that the packer has three separate packing points when in packing position, as shown in Fig. 2,—two against the wall of the well or the interior of the casing and one against the surface of 85 the well tubing. It will also be noted that by reason of the fact that the bolster 2 is secured to the tubing, said bolster is prevented from moving upward and compressing the sleeve 3 in case the bolster should 90 meet any obstruction while the packer is being lowered into the well.

The sleeve constructed as above becomes hard upon drying, but will quickly soften in the presence of water in the well, thus producing an ideal packing. Any other cement 95 than that above described having the same properties may be employed.

Referring to Fig. 6, it will be observed that instead of the standard tube coupling 100 13 holding all of the parts together, a standard pipe coupling 15 is secured on the lower end of the gas relief pipe 6, and the upper end being screw-threaded into the gland 7 said pipe 6 serves to hold all of the parts together and in position, with the exception of the cup 9 and the cap 10. Fig. 8 shows a form of the invention employed when no gas relief pipe is used.

It will be observed that the packer is of 110 simple construction, composed of parts which are cheaply and readily manufactured and assembled, and that the packing sleeve, before placing in the well, is firm and rigid, but upon placing in the well becomes 115 softened with the water, thereby rendering it plastic whereby it effects a complete packing of the well; that it will not become hard or set in the well; and that it may be readily removed from the well for inspection, repairs or replacement.

What is claimed is:

1. In an oil well packer, the combination 125 of a plastic packing sleeve surrounding the well tubing, a fixed abutment on which said sleeve rests, and means longitudinally movable on the well tubing above the sleeve and transmitting the pressure of the superposed column of water in the well to said sleeve.

2. In an oil well packer, the combination 130

- of a plastic packing sleeve comprising a mass of loose fibers and a binder, a well tubing surrounded by said sleeve, a fixed abutment on which said sleeve rests, and means longitudinally movable on the well tubing above the sleeve and transmitting the pressure of the superposed column of water in the well to said sleeve.
3. In an oil well packer, the combination of a plastic packing sleeve comprising a mass of asbestos fibers and a soap-stock lubricant, a well tubing surrounded by said sleeve, a fixed abutment on which said sleeve rests, and means longitudinally movable on the well tubing above the sleeve and transmitting the pressure of the superposed column of water in the well to said sleeve.
4. In an oil well packer, the combination of a plastic packing sleeve composed of asbestos fiber, a resin and a soap-stock lubricant, a well tubing surrounded by said sleeve, a fixed abutment on which said sleeve rests, and means longitudinally movable on the well tubing above the sleeve and transmitting the pressure of the superposed column of water in the well to said sleeve.
5. In an oil well packer, the combination of the well tubing, an abutment fixed on said tubing, a plastic ring supported by said abutment and surrounding said tubing, a rigid head or follower longitudinally movable on said tubing above the sleeve, and means above the head, or follower, and transmitting the pressure of the superposed column of water in the well to said head or follower.
6. In an oil well packer, the combination of the well tubing, a bolster or abutment fixed on said tubing, a plastic sleeve supported on said abutment, a head mounted to move longitudinally on said tubing above said sleeve, packing material supported in a recess in said head and surrounding said tubing, a packing gland working in said recess above said packing and exposed to the pressure of the superposed column of water in the well.
7. In an oil well packer, a packing sleeve composed of asbestos fibers and a composition of resin, mineral oil, tallow, soda lye and water.
8. In an oil well packer, a packing sleeve composed of a mass of loose fibers and a soap composition mixed with a mineral oil and a resin.
9. In an oil well packer, the combination of a packing sleeve composed of loose fibers and an air-hardening water-softening binder.
10. In an oil well packer, a packing sleeve composed of asbestos fibers and an air-hardening water-softening binder.

In testimony whereof we have signed this specification.

SHELTON T. CAMERON.
EDWARD R. INMAN.
